UNITED STATES PATENT OFFICE.

EUGEN BLASBERG, OF DUSSELDORF, GERMANY.

LADDER.

SPECIFICATION forming part of Letters Patent No. 503,120, dated August 15, 1893.

Application filed March 6, 1893. Serial No. 464,695. (No model.)

To all whom it may concern:

Be it known that I, EUGEN BLASBERG, a subject of the German Emperor, residing at Dusseldorf, Germany, have invented certain 5 new and useful Improvements in Ladders, of which the following is a description.

This invention relates to an extension ladder in which the side bars of the lower ladder are provided with pivoted stops or levers 10 which, when swung down, project below the rungs of the upper ladder to support the same.

In the accompanying drawings: Figure 1 is a vertical section of my improved ladder; Fig. 2 a front view thereof; Fig. 3 a side elevation of the catch showing it lowered; Fig. 4 a cross section on line x, x , Fig. 3; Fig. 5 a front view of Fig. 3; Fig. 6 a side elevation of the catch showing it partly raised; Fig. 7 a similar elevation showing it completely 20 raised and Fig. 8 a cross section on line y, y , Fig. 7.

The letters a , represent the side bars of the lower ladder.

b are the side bars of the upper ladder and 25 c, c , a pair of encircling straps that permit the upper ladder to be lowered or raised.

To the inner face of the side bars a , there is pivoted a stop or lever k , which when in a horizontal position, extends beneath the 30 rungs, steps or projections b' of the upper ladder. To the side bars a , there are secured above and preferably also below the lever k , the stops s, s' , which are arranged diagonally 35 opposite each other as shown. These stops maintain the lever in a horizontal position against pressure applied to the upper edge of its free end. Thus it will be seen, that when the lever is swung down (Fig. 3) to project be-

neath one of the rungs b' of the upper ladder, it will securely lock such ladder in position. 40 The upper ladder can be raised freely as the rungs when passing the lever will tilt the same. I prefer to weight the lever at its free end, so that it will automatically assume its horizontal position when no longer tilted by 45 the rungs and will thus lock the upper ladder in place.

When the upper ladder is to be lowered, it is first slightly raised, to liberate lever k , and then such lever is swung up (Figs. 6 and 7) 50 to clear the rungs. In its upright position, the lever k , can be held, either by being swung beyond its center, or it can be engaged by a spring catch d , pivotally secured to side bar a .

What I claim is—

1. The combination of a lower ladder with an upper sliding ladder, an embracing strap, a lever secured to the lower ladder and projecting beneath the rungs of the upper ladder and with a stop that engages the upper edge 60 of the lever, substantially as specified.

2. The combination of a lower ladder and an upper ladder, with the lever k , pivoted to the side bar of the lower ladder and adapted to be projected beneath the rungs of the upper 65 ladder and with diagonally arranged stops s, s' , on opposite sides of the lever and a catch d , substantially as specified.

In testimony whereof I have signed this specification in the presence of two subscr- 70 ing witnesses.

EUGEN BLASBERG.
